DRAFT GEAR

Donald F. Sproul, Chicago, Ill., assignor to Cardwell Westinghouse Company, a corporation of Delaware

Application February 27, 1933, Serial No. 658,719

3 Claims. (Cl. 213—38)

The invention relates to draft gears of the type in which the spring elements are carried by a transverse rod and cooperate with laterally movable wedge-blocks.

Its objects are to simplify gears of this type and increase their durability.

A preferred embodiment of the invention is hereinafter described, and is illustrated in the accompanying drawings, in which

Fig. 1 is a detail plan of the device, some of its parts and portions of a car frame being shown in section, the gear being shown in release position;

Fig. 2 is a detail central transverse section;

Fig. 3 is a view similar to Fig. 1, the gear being under full compression;

Figs. 4 and 5 are views in perspective of the two forms of wedge-blocks employed in the device.

A pair of draft sills are shown at 10, 10, and are provided with draft and buffing lugs 11, 12, with which the gear cooperates. The gear comprises a pair of follower elements 13, 14, which preferably take the form of hollow casings and are identical in form. Each of these followers comprises a transverse wall 15, having an inwardly facing surface, and a rear wall 16, engageable with the draft or buffing lugs and sustaining a pressure in the one instance of the coupler butt 17, and in the other of the yoke 18.

These follower elements further comprise inwardly projecting top and bottom walls 19, 20, which are centrally longitudinally channeled, as shown at 21, to provide guide-ways for certain of the wedge elements of the gear; and also with forwardly projecting side walls, as 22, which strengthen the structure.

Seated against the inner surface of each of the follower elements is a double faced wedge-block 23, 24, the width of the bases of these blocks being somewhat less than the interior width of the follower element and their vertical dimension being approximately that of the interior of the follower chambers. These blocks are provided with top and bottom forwardly projecting bosses 25, 26, which project above and below the wedge-blocks, such extensions being carried back to the base of the block and serving as guides cooperating with the channels 21. The extreme length of the two wedge-blocks 23, 24, including their bosses 25, 26, is such that when they make contact they serve as limiting stops and carry wholly or partly the overload.

A pair of laterally disposed double faced wedge-blocks 27, 28, are interposed between the blocks 23, 24, and cooperate with their wedge faces.

The length of the base of each of the blocks 27, 28, is preferably the same as the combined length of the blocks 23, 24. The end portions of the blocks 27, 28, are flattened, as shown at 29, and seat against the inner transverse walls of the follower elements upon full compression, whereby these lateral wedge-blocks also function as limiting stops.

A spring rod 30 extends transversely through the gear and the sills 10, the wedge-blocks 27, 28, 10 and the sills being apertured for their accommodation, the apertures in the sills being elongated, as indicated at 31, to provide for lateral movement of the rods. The bosses 25, 26, are spaced apart to clear the rod, and the side walls 22 of the follower elements are slotted for the same purpose, as indicated at 32.

A pair of helical springs 33, 34, are mounted upon the end portions of the rod 30, outside of the sills 10, and react between spring seats, as 35, 20 sleeved upon the rod and bearing upon the outer faces of the blocks 27, 28, and spring seats 36, in the form of nuts, applied to the outer ends of the rod.

The top and bottom walls 19, 20, and side walls 25 22 of the follower elements are somewhat shorter than the combined overall length of the wedge-blocks 23, 24, and the length of the wedge-blocks 27, 28, and do not, therefore, make contact upon full compression of the gear, as plainly indicated 30 in Fig. 3. These walls constitute the weakest portions of followers of the chambered type, and in the gear as described the overload is transmitted to and through the rearward end portions of the follower elements, which are made 35 amply strong to carry them.

The wedge faces 37 of the blocks 23, 24, terminate short of the bases and apexes of these blocks, as indicated at 38, 39, and are of such length that the faces of the blocks 27, 28, overlap them on full release and full compression, thereby avoiding the formation, by wear, of shoulders adjacent the ends of these faces. Upon full release of the gear the parts are relatively positioned as shown in Fig. 1.

Upon compression of the gear either in draft or buff one of the followers is advanced, and with it the double faced wedge-block seated against its inner transverse face. This advance carries forward, also, the wedge-blocks 27, 28, spreading 50 them apart by the conjoint action of the two blocks 23, 24, against the resistance of the springs 33, 34. The rod 30 is carried forward with the wedge-blocks 27, 28. Upon full compression of the gear the forwardly projecting bosses 55

25, 26, of the wedge-blocks 23, 24, come into contact, and the blocks 27, 28, engage the transverse walls of the follower elements, through which the overload is transmitted directly to 5 the sills.

If desired either of the two limiting means may be relieved of that duty by being shortened, but by utilizing both the load is distributed over the entire area of the followers. In either case 10 the side walls of the casing, which are necessarily comparatively light, are relieved of the duty of sustaining the overload.

I claim as my invention—

1. In a draft gear, in combination, a pair of 15 stop-engaging end plates, top and bottom plates extending forwardly from the end plates and having longitudinal guide channels, a double faced wedge projecting from the inner side of each plate and having forwardly projecting 20 bosses of such height and length and disposition that they engage in the guide channels and make contact on full compression, a pair of double faced wedge-blocks interposed between the wedge faces of the first-named blocks and spring means 25 urging the second-named blocks toward the longitudinal center line of the gear.

2. In a draft gear, a pair of end plates each having forwardly projecting, longitudinally channeled flanges, a pair of double faced wedge-

blocks one associated with the inner face of each of the end plates, such blocks being provided with vertically and forwardly projecting bosses for engagement with the channels and adapted to engage as limiting stops on full compression of the gear, a pair of laterally disposed wedge-blocks each engaging a face of each of the triangular blocks, a rod extending transversely through the gear, spring resistance means carried on the end portions of the rod and bearing on the laterally disposed wedge-blocks, and spring seats on the rod for the outer ends of the springs.

3. In a draft gear, in combination, a pair of 15 stop-engaging end plates, top and bottom plates extending forwardly from the end plates and having longitudinal guide channels, a double faced wedge projecting from the inner side of each plate and having forwardly projecting bosses of such height and length and disposition that they engage in the guide channels and make contact on full compression, a pair of double faced wedge blocks interposed between the wedge faces of the first-named blocks and being of such length that they engage the two 20 stop-engaging plates on full compression, and spring means urging the second-named blocks toward the longitudinal center line of the gear.

DONALD F. SPROUL.
